UNITED STATES PATENT OFFICE.

STEVEN SALOP, OF YOUNGSTOWN, OHIO.

BOOK-LOCK.

1,349,857.

Specification of Letters Patent. Patented Aug. 17, 1920.

Application filed April 30, 1920. Serial No. 377,767.

To all whom it may concern:

Be it known that I, STEVEN SALOP, citizen of the United States, residing at Youngstown, Haselton Station, in the county of 5 Mahoning and State of Ohio, have invented certain new and useful Improvements in Book-Locks, of which the following is a specification.

This invention relates to book locks, and 10 has for its object the provision of means for preventing access to the contents of the book inclosed thereby, unless a key is first used to unlock the book inclosing means.

A further object of this invention is to 15 provide means whereby the locking device may be adjusted to hold books of various thicknesses, or to encompass several books of the same length and width.

To attain the aforesaid and other objects, 20 I employ the device shown in its preferred form in the accompanying drawings, in which—

Figure 1 is a perspective view of a book and of my device in the locked position 25 thereof.

Fig. 2 is a plan view of my device as it appears when unlocked and opened out into its unfolded position ready for the reception of a book.

Fig. 3 is a vertical section taken through 30 the lock and book approximately on line 3—3 of Fig. 1.

Fig. 4 is a horizontal section taken through the lock approximately on line 35 4—4 of Fig. 3.

Fig. 5 is a vertical section of the means for adjusting my device to books of various thicknesses.

A bottom member 10, on which the book 40 11 rests, is made in the form of a cross, having main arms 13, the distance between the ends of which is slightly greater than the width of the book, and having branch arms 12, in which the distance between the ends 45 is slightly greater than the length of the book to be locked. Adjustable sections 15, which will be described more fully herein-after, are all similarly constructed, and serve to connect the various arms of lower 50 member 10 with the upper locking sections by means of hinges 16, said sections 15 being connected to said lower member 10 by means of hinges as 14.

For forming a complete locking strap 55 lengthwise of the book, upper locking sections 17 are hinged to adjustable sections 15,

each of said locking sections having a hole 18 near the end thereof adapted to engage pin 19 secured near the end of upper locking section 20. Said pin 19 is made long enough 60 to pass through holes 18 of members 17 and to project through said holes an amount sufficient to allow said pin to engage part of the locking structure 22, carried by upper arm 21, when the various sections and arms 65 are folded around the book, a hole 23 being provided near the end of arm 21 through which said pin may be passed.

A lock structure 22 is secured to the end of arm 21, a keyhole 24 being cut in the upper face of said lock, and a locking catch 25, pivoted on pin 26, being arranged to be pressed into slot 27 in the upper end of pin 19 when the various parts are folded up, due to the action of spring 28. 75

Vertical sections 15 are each made in two parts, one part 28 being hinged to the upper foldable members of my device by hinge 16 and the other part 29 being hinged to the end of the stationary cross 10 by hinge 14. 80 Part 29 has a projecting shoulder 30 at its upper end, to which is fastened pin 31, having knob 32 at the end thereof. A vertically disposed slot 33 is cut in part 28 to allow pin 31 to pass through and to be adjusted 85 vertically with respect to said part, and on the inner face of said member 28, a series of horizontally arranged depressions 34 are cut partly through the member, said depressions being made wide enough on each side 90 of slot 33 to receive shoulder 30 of part 29.

To adjust the parts 28 and 29 to take books of different thicknesses, knob 32 is pressed inwardly, removing shoulder 30 from that one of depressions 34 with which it happens 95 to be in engagement, whereby part 29 is swung slightly backwardly about hinge 14. After disengaging shoulder 30 from depression 34, a downward pressure on knob 32 causes part 29 and the cross 10 attached thereto to move downwardly relatively to part 28, shoulder 30 engaging another one of depressions 34 when the pressure on knob 32 is released. The remaining sections 15 may be similarly adjusted. 100 105

To lock up a book, arm 20 is first folded about its hinge 16 through an angle of approximately 180°, so that section 15 attached thereto assumes a vertical position, (Fig. 1) and pin 19 an upstanding position. 110 Arms 17 are now similarly folded, pin 19 engaging holes 18. The last member to be

folded is arm 21, pin 19 engaging hole 23 thereof in the folded position. To allow catch 25 to engage slot 27 of pin 19 for locking the device, a key is inserted through 5 keyhole 24, and the key turned sufficiently to prevent catch 25 from striking pin 19. When the catch and slot are in apposition, the key is released and the catch drops into slot 27, urged thereto by spring 28. In un- 10 locking the device, the key must be used to withdraw catch 25 from slot 27 before the part can be unfolded.

It will be seen that a book held by my improved lock cannot be opened sufficiently to 15 have any portion of the contents read or tampered with, and can be used to advantage with loose leaf and other types of account books in general commercial use.

I claim:

- 20 1. A book lock comprising a rigid cross shaped member, sections adjustable to the thickness of a book each comprising two non-rotatable but relatively movable parts, hinges joining one of the parts of each of 25 said sections to one end of said member, a series of upper foldable arms, hinges joining each of the other of said parts to one end of each of said arms, and means for locking the other ends of said arms together.
- 30 2. In a book lock, a rigid cross shaped

member, sections adjustable to the thickness of a book each comprising a slotted part having horizontal depressions therein, an inner part having shoulders thereon for engaging said depressions and a pin passing through 35 said slotted part and attached to said inner part for pushing on said inner part to disengage said parts from each other transversely, hinges joining the lower end of each of said inner parts to an end of said cross shaped 40 member, hinges joining the upper ends of each of said slotted parts to an end of each of said arms, and means for locking the other ends of said arms together.

3. In a book lock, a rigid member, fold- 45 able arms, adjustable foldable means connecting said arms and said rigid member, each comprising a slotted part hinged to one of said arms and having horizontal de- 50 pressions therein, an inner part hinged to the rigid member, a shoulder at the upper end of a said inner part adapted to engage said depressions, and a pin passing through said slotted part for manipulating said inner part, and means for locking said arms to- 55 gether.

In testimony whereof I have affixed my signature this 24th day of April, 1920.

STEVEN SALOP.
